THE SILVER SKIRT AND WIRE MANUFACTURING COMPANY, OF NEW YORK, N. Y., ASSIGNEES OF T. S. SPERRY.

Letters Patent No. 46,718, dated March 7, 1865; reissue No. 2,277, dated June 5, 1866; reissue No. 2,485, dated February 19, 1867.

IMPROVEMENT IN THE MANUFACTURE OF SKIRT WIRE.

The Schedule referred to in these Letters Patent and making part of the same.

TO ALL WHOM IT MAY CONCERN:

Be it known that we, the Silver Skirt and Wire Manufacturing Company, of the city, county, and State of New York, are the assignees of Letters Patent of the United States granted to T. S. SPERRY for a new and useful Improvement in the Manufacture of Skirt Wire; and we do hereby declare that the following is a full, clear, and exact description thereof, which will enable those skilled in the art to make and use the same, reference being had to the accompanying drawings forming part of this specification, in which—

Figure 1 represents a side elevation of this invention.

Figure 2 is a longitudinal section of the same.

Similar letters of reference indicate corresponding parts.

Skirt wire, as previously manufactured, is covered with cotton or other fibrous material, laid on by braiding or in any other suitable manner. This covering labors under the great disadvantage that it is liable to wear out or pull off after a short time, whereby the skirt becomes damaged. To avoid this disadvantage, and to produce a durable covering for skirt wire, is the object of this invention, which consists in the use of thin metal wire for the purpose of covering skirt wire, said wire to be applied by braiding or simply by winding it on in such manner that a durable covering for skirt wire is obtained which will effectually protect said wire and not be liable to pull off or wear out. A represents a piece of skirt wire made in the usual manner, either single or double, as may be desirable. This wire is covered by metal wire B, which may be wound on as shown in the drawing, or which may be braided on, or which may be applied in any other suitable manner. For the purpose of covering skirt wire, iron or brass wire coated with tin, zinc, or other non-corrosive material, is used by preference; and by using such wire, a covering can be produced which gives to the skirt wire a very handsome appearance, and which also will be durable and not liable to come off. But if the use of such non-corrosive wire should be too expensive, ordinary plain iron or brass wire may be used, and if the same is thin enough and properly annealed, it can be laid on by braiding precisely like cotton, thread, or other fibrous material, and a skirt wire can be produced which will be strong, durable, and well adapted to hoop skirts.

We do not claim covering a central core with a wrapping or coil of wire, as that has before been proposed; but what we claim as new, and desire to secure by Letters Patent, is—

Skirt wire protected wholly or partially by metal wire, substantially as and for the purpose described.

SILVER SKIRT AND WIRE MANUFACTURING COMPANY,
